CONTROL NEEDLE FOR A SPRAY DEVICE

Carl Åke Löfgren, Hagersten, Sweden, assignor to Svenska Maskinaktiebolaget Greiff, Stockholm, Sweden, a Swedish joint-stock company

Filed June 2, 1960, Ser. No. 33,417

Claims priority, application Sweden June 11, 1959
2 Claims. (Cl. 239—408)

This invention relates to control needles for spray devices and, more particularly, to control needles for paint spray guns.

In paint spray guns, the needle which closes and opens the paint outlet of the spray tip is conventionally made of a metal such as steel. The use of steel is very disadvantageous inasmuch as the abrasive action of the paint will alter the shape of the needle so that the needle subsequently cannot close the outlet the shape of which is also altered and thus the gun will leak.

I have found that the substitution of a plastic material in place of metal for forming needles of the above indicated type is not satisfactory. Thus, for example, certain types of paint can soften these plastic materials so that they cannot withstand pressure, thus enabling the needle to bend so that the closing of the paint outlet by the needle is less efficient because the tip of a plastic needle enters the associated fluid outlet at a slight angle whereby the needle does not completely close the outlet so that leakage is possible.

It is an object of the invention to provide an improved needle and thereby an improved spray device and paint spray gun which avoids the difficulties noted above, these difficulties being inherent in the use of needles made entirely from metal or entirely from plastic.

To achieve this object, I employ a needle which is partly of a rigid material such as metal and partly of a plastic material such as nylon. The plastic material is employed as the tip of the needle and is that portion of the needle which enters the spray outlet. The rigid material provides the necessary strength and control.

Other objects of this invention, as well as features and advantages thereof, will be apparent from the following detailed description as illustrated in the accompanying drawings, in which:

FIG. 1 illustrates a paint spray gun partially in section and embodying a needle control provided in accordance with the invention;

FIG. 2 illustrates, partially broken away and partially in section, the spray outlet, as well as the associated needle tip provided in accordance with the invention; and

FIG. 3 is a cross-sectional view of the structure of FIG. 2 taken along line III—III.

In FIG. 1 is illustrated a paint spray gun 10 comprising a handle 12, a trigger 14, an adapter 16 for connection to a source of paint, an adapter 18 for connection to a source of a pressure medium such as compressed air, a barrel or body 20 having an elongated chamber C and adjustment knobs 22 and 24.

At one end of the barrel 20 is a substantially cylindrical spray outlet opening 26 surrounding which is an annular orifice 28 through which flows the compressed air. This compressed air in conventional manner aspirates the paint in the form of a spray via spray outlet opening 26, the flow of the paint from adapter 16 through discharge opening 26 being controlled and obturated by means of control needle 30, which is under the control of trigger 14 and is supported in a bushing or bearing 31. It will be noted that a needle made entirely from nylon would wear at bushing 31 and cause the gun to leak.

FIG. 2 illustrates spray outlet opening 26 in a greater detail and, as can be seen, there is included an outermost

2

cylindrical portion 32 into which opens an inner conical portion or seat 34. For purposes of manufacturing and facilitating paint flow, there is also provided a further conical portion 36.

5 Needle 30 consists of two sections, to wit, rigid elongated stem section 38 which is a rigid direction-controlling force-transmitting rod made of metal such as, for example, stainless steel and a section 40 which is a yieldable resilient section of paint resistant plastic such as, for example, nylon.

10 In an ideal spray gun, needle 30 and opening 26 have perfectly circular cross-sections and are perfectly aligned in an axial sense. Under such conditions, the use of a needle made entirely of metal might be possible, although even in this case, the abrasive action of the substance to be sprayed would soon destroy the ability of these components to mate. FIG. 2, however, illustrates the usual situation in which the tolerances of manufacture displace the needle 30 from a true axial alignment with the passage 26 and, in this instance, the needle 30 can be seen striking the edge of the passage 26 as indicated at 42.

15 The passage or opening 26 is conveniently given a configuration as illustrated in FIG. 2 whereby it comprises a cylindrical portion 32 and a conical portion 34.

20 The tip of needle 30 is also given this configuration so that section 40 includes a cylindrical portion 44 adapted to cleanse residue materials from cylindrical portion 32, as well as a conical portion 46. The cylindrical and conical portions of both the outlet 26 and resilient section

25 40 are, respectively, concentric or coaxial and contiguous. With reference to deformable portion 40, conical portion 46 tapers into cylindrical portion 44 (which itself terminates in a conical portion 48 for purposes of manufacture). The tip, it will be noted, in order to be somewhat flexible is of an axial length substantially greater than its diameter or transverse dimension and extends as a solid mass for a substantial distance (e.g., at least twice its diameter) from the end of stem 38.

30 The sections 38 and 40 of needle 30 are provided with 40 mating male and female members. Preferably, portion 38 is provided with an extension or anchoring device 50 having a head 52 or some other irregular projection which is accommodated in a socket 54 provided in resilient section 40. Preferably, as a matter of manufacturing 45 procedure, the tip 40 is molded directly on the rigid section 38.

35 It is to be noted, in connection with the manufacture of a control needle provided in accordance with the invention, that the mold form for the tip can be made so as to correspond directly with the desired final shape of the tip. Therefore, after molding, the needle is ready for use and requires no machining.

40 FIG. 3 indicates by dotted lines the shape of outlet 26 and, particularly, of cylindrical portion 32 thereof following the abrasive action of the substance to be sprayed. It will be noted how this abrasive effect changes the circular hole to an oval shape to which only a plastic tip can conform.

45 In conclusion, it is noted that the comparatively large tolerances required for the manufacture of spray devices, as well as the abrasive action of the substance to be sprayed, has the unfortunate result that a control needle for a spray outlet will rarely, if ever, be concentric with the latter. It will, therefore, be impossible for the control needle to operate effectively and efficiently unless this needle is provided as contemplated by the invention. The invention contemplates the providing of a deformable tip which facilitates the conformance of this tip with the shape of an associated outlet and, at the same time, the

50 invention contemplates preserving sufficient strength in the needle by the use of a rigid section made of, for example, metal. More particularly, in the preferred em-

bodiment of the invention where the tip is of nylon (which is substantially inert with respect to paint) and the major portion of the body is of steel, the tip of nylon is about one-tenth of the overall length of the needle. It is to be noted that nylon, which is conventionally employed for bearings, inherently provides a friction-free surface on the tip which inures to the benefit of the invention.

There will now be obvious to those skilled in the art many modifications and variations of the structure set forth above. These modifications and variations will not, however, depart from the scope of the invention if they are defined by the following claims.

What is claimed is:

1. A paint spray device comprising a body provided with an elongated chamber for a fluid to be sprayed, said body including a substantially conical seat at an end of said chamber and being provided with a substantially cylindrical opening connected to and concentric with said seat and through which said fluid leaves said chamber; a needle extending through said chamber and including an elongated rigid stem including an irregular end portion and a tip on said stem and engaging said irregular end portion, the engagement between said tip and irregular end portion preventing rotational displacement therebetween, said tip including a first cylindrical portion of a diameter equal to that of the stem, a conical portion on said first cylindrical portion and of a shape substantially corresponding to that of said seat and a second cylindrical portion extending from said conical portion and of a length substantially equal to that of said cylindrical opening whereby the second cylindrical portion is adapted to cleanse said opening of residue materials therein, said tip being of a nylon-like material which is substantially inert with respect to paint and which is substantially more deformable than said rigid stem whereby said tip is adapted to conform to the shape of said seat as the latter wears, said tip being of a length substantially greater than its transverse dimension and extending as a solid mass and for a substantial length from the rigid stem; means coupled to said needle for yieldably urging said tip into said seat and cylindrical opening and maintaining the tip therein whereby to conform said tip to the shape of said seat, and means to move said needle to withdraw said tip from said seat to permit said fluid to pass through said opening.

2. A paint spray device comprising a metal body provided with an elongated chamber for a paint to be sprayed, said body including a substantially conical seat at an end of said chamber and being provided with a substantially cylindrical opening connected to and concentric with said

seat and through which said paint leaves said chamber; a needle extending through said chamber and including an elongated metal stem including an irregular end portion, and a tip on said stem and engaging said irregular end portion, the engagement between said tip and irregular end portion preventing rotational displacement therebetween, said tip including a first cylindrical portion of a diameter equal to that of the stem, a conical portion on said first cylindrical portion and of a shape substantially corresponding to that of said seat and a second cylindrical portion extending from said conical portion and substantially corresponding to said cylindrical opening whereby the second cylindrical portion is adapted to cleanse said opening of residue paint therein, said tip being of a nylon-like material which is substantially inert with respect to paint and which is substantially more deformable than said metal stem whereby said tip is adapted to conform to the shape of said seat and opening as said body wears, said tip being of a length substantially greater than its transverse dimension and extending as a solid mass and for a substantial length from the metal stem; means coupled to said needle for yieldably urging said tip into said seat and cylindrical opening and maintaining the tip therein whereby to conform said tip to the shape of said seat, and means to move said needle to withdraw said tip from said seat to permit said paint to pass through said opening; bearing means in said body and slidably supporting said metal stem; and means in said body for discharging a pressure medium adjacent said cylindrical opening for atomizing said paint.
